DRIVING MEANS FOR THE SLIDES OF
MACHINE TOOLS

Oscar E. Rosen, Detroit, Mich.

Application October 30, 1940, Serial No. 363,523

2 Claims. (Cl. 90—21)

The present invention relates to machine tools and more specifically to operating means for the work table or other movable elements thereof.

Still more specifically, the invention relates to duplicating machines wherein the work and cutter are moved relatively by automatic means in response to and controlled by the action of a tracer moving over a pattern.

Among the objects of the invention is actuating means for such movable elements, including a small motor of relatively high speed and speed reducing means which permits the direct drive of such elements even on large machines.

Another object is a speed reducing means which, though non-reversible in ordinary use, nevertheless will slip under extraordinary stresses and thereby act as a safety device.

Other objects will readily occur to those skilled in the art upon reference to the following description and the accompanying drawings in which:

Figure 1 is a side elevation, partially in section, showing the complete combination.

Figure 2 is a section on line 2—2 of Figure 1.

Figure 3 is a section on line 3—3 of Figure 1.

Figure 4 is a section on line 4—4 of Figure 1.

Figure 5 is a view similar to Figure 3 but showing a modified structure.

In the drawings, there is indicated at 10 a rack such as is fixed to the cutter head or other slide of a conventional milling or other cutting machine or machine tool. This rack 10 is moved longitudinally to move the slide back and forth or up and down, as the case may be, by means of a gear 11, actuated in the conventional machine by suitable gearing, and, in the present case by being fixed to a rotatable shaft 12.

In the present device, the shaft 12 is rotated in one direction or the other by a reversible motor 15 preferably of the type shown and described in United States Patent No. 2,138,208, issued November 29, 1938, or other suitable type. In the patent and in the present device, the motor is indicated as a hydraulic motor controlled through the action of a tracer upon a pattern.

As indicated, the shaft 15a of motor 15, extends from the motor housing into the larger housing 16 where it is keyed in the adjacent end of a sleeve 17, the shaft 15a, sleeve 17, and shaft 12 being in axial alignment.

The opposite end of sleeve 17 is enlarged, as shown, and has its outer cylindrical surface somewhat eccentric as indicated at 18, and upon the eccentric portion carries the inner race of anti-friction ball or roller bearing 19.

Mounted upon the outer race of the bearing 19

is a thick disc 20 which carries fixed upon its outer periphery a band of friction producing material 21, such as a suitable brake lining, and is also provided with a plurality of openings 22 for the reception of studs 23, these and their bushings 24 of friction reducing material being somewhat smaller than the openings 22.

Since the disc 20 and its bearing 19 are mounted upon the eccentric portion 18 of sleeve 17, the disc 20 itself will also be eccentric to the axis of the shaft 15a. Surrounding the disc 20, but concentric with the shafts 15a and 12, is a cup member 30, the internal diameter of which is only slightly larger than the over-all diameter of disc 20 and band 21, the dimensions of these parts being such that when they are assembled, there will be considerable pressure between the disc 20 and cup 30 on one side with a slight clearance diametrically opposite.

Cup 30 is fixed by means of suitable screws 31 to a flange 32 forming a part of or fixed to shaft 12, being thus a functional part of the latter, while the inner end of the shaft extends into and is piloted by the inner end of sleeve 17, the shaft end, shown at 12a, being surrounded by the small roller bearing 12b.

The shaft 12 is mounted in a suitable bearing 33 in a cover plate 34 for housing 16.

The pins 23, above referred to and of which there are preferably a plurality, six being shown, are provided for the purpose of maintaining the disc 20 against rotation when the motor 15 is operated. These pins 23 are fixed in a second disc 40, rotatably carried upon an inwardly extending flange 41 concentric with the shafts 12 and 15a, the disc being held against axial movement by a collar 42.

This disc 40 is, as shown, a worm gear, having spiral teeth 43 on its periphery, adapted to coact with a worm 44, which worm is mounted tangentially thereto in the casing 16 in bearings 45 and 46 and operable by means of a hand wheel 47, or suitable driving mechanism.

Bearing 46 is carried in a block 48, movable vertically upon suitable rods 49 and capable of being fixed against upward movement or pressed down tightly by a screw 50. When the screw 50 is tightened downwardly, it will jam together the worm 44 and gear 43 and lock the latter against movement. Slightly loosening the screw 50 will permit rotation of the worm 44 and thereby the gear 43 for a purpose mentioned later.

Suitable oil passages 60 are shown as providing for the lubrication of the pins 23 in their surrounding bushings.

In order to prevent overrun of the motor 15 and undesirable movement of shaft 12, the two-way acting brake shown in detail in Figure 4 is located between the motor and housing 16. In this figure the shaft 15a is shown as carrying a disc or drum 65, against the edge of which act two brake shoes 66, pivoted as at 67 and pressed against the disc 65 by springs 68 acting on their free ends. The spring pressure may be arranged to be adjustable in any suitable manner as by the screws 69.

In the operation of the device, the slide to which it is attached may be moved quickly to its approximate position by loosening screw 50 and turning the hand wheel 47. This causes the rotation of discs 40 and 20, these being connected by pins 23 and, since disc 20 frictionally engages cup 30, this also rotates and, in so doing, rotates shaft 12.

When the approximate adjustment has thus been accomplished and the screw 50 tightened, thus fixing the pins 23 against movement, the motor 15 is put into operation. With the motor 15 running, the disc 20, carried upon the eccentric 18 will move around upon the inner periphery of cup 30, and, since the disc 20 is fixed against rotation by the pins 23, the cup 30 and the shaft 12 is forced to turn.

If, however, the resistance of the slide, due to any reason whatever, becomes sufficiently great, the friction between disc 20 and cup 30 will be overcome and these parts will slip, thereby preventing breakage. Further, with only a slight eccentricity of sleeve 18, the reduction in speed from shaft 15a to shaft 12 becomes so great that a very small motor 15 is capable of exerting enormous torque upon the driven shaft 12.

In applying the device to any machine, the housing 16 or plate 34, or both, will be fixed to any suitable stationary part thereof.

The structure so far described, is, as indicated, particularly suitable for milling machines or the like, and, while such structure may also be used on lathes, it is desirable to modify it somewhat to permit turning the work set up in the lathe quickly and easily.

Figure 5 shows such a modified structure.

In this figure, the modification is shown to consist in omitting the 44 and the coating teeth

43 from the disc 40 together with the worm locking means.

Instead there is used a disc 40a having a substantially smooth periphery and a brake shoe 44a arranged to act on said periphery.

This shoe 44a may be actuated in any suitable manner and is shown as carried by a screw 50a in turn actuated by a suitable hand wheel 47a.

Such an arrangement permits a quick and easy release of the mechanism and also enables wide adjustment of the reaction resistance.

Now having described the invention and its preferred embodiment, what is claimed is:

1. Speed reducing means for motor driven elements consisting of a cylindrical cup fixed to the driven element, a disc within said cup and eccentric thereto and arranged to contact with the interior cylindrical wall thereof, friction producing material fixed to one of the contacting surfaces, motor driven means for moving said disc in a path concentric to said cup while maintaining the contact therewith, and means for preventing rotation of said disc, said last mentioned means consisting of a plurality of pins

20 extending into openings in said disc and mounted in an element coaxial with said cup and means for rotating said element whereby to rotate said cup, disc, and element as a unit and means for fixing the said element against rotation.

2. In combination with a slide-moving rack of a machine tool, a pinion and drive therefor, said pinion drive consisting of a shaft carrying said pinion and fixed axially to a cylindrical cup, a disc within said cup and eccentric thereto and arranged to contact with the interior cylindrical wall thereof, friction producing material fixed to one of the contacting surfaces, motor driven means for moving said disc in a path concentric to said cup while maintaining the contact therewith and means for preventing rotation of said disc, said last mentioned means consisting of a plurality of pins

30 extending into openings in said disc and mounted in an element coaxial with said cup and means for rotating said element whereby to rotate said cup, disc, and element as a unit and means for fixing the said element against rotation.

3. In combination with a slide-moving rack of a machine tool, a pinion and drive therefor, said pinion drive consisting of a shaft carrying said pinion and fixed axially to a cylindrical cup, a disc within said cup and eccentric thereto and arranged to contact with the interior cylindrical wall thereof, friction producing material fixed to one of the contacting surfaces, motor driven means for moving said disc in a path concentric to said cup while maintaining the contact therewith and means for preventing rotation of said disc, said last mentioned means consisting of a plurality of pins

40 extending into openings in said disc and mounted in an element coaxial with said cup and means for rotating said element whereby to rotate said cup, disc, and element as a unit and means for fixing the said element against rotation.

OSCAR E. ROSEN.
